UNITED STATES PATENT OFFICE

ALBERT O. BUCKIUS, OF CLEVELAND, OHIO, ASSIGNOR TO NATIONAL MALLEABLE AND STEEL CASTINGS COMPANY, OF CLEVELAND, OHIO, A CORPORATION OF OHIO

SIDE FRAME

Application filed February 3, 1931. Serial No. 513,062.

This invention relates to improvements in side frames for railway car trucks and has particular reference to the provision of suitable means to be added to a frame commonly known as the Andrews type for the purpose of readily adapting it for the reception of a roller bearing journal box.

The Andrews type of frame is a cast structure having integral tension and compression members and the journal boxes are adapted to be bolted to extensions at the ends of the frame. Further support for each of the boxes is provided by a tie bar or plate which is riveted or otherwise secured to the frame casting and connected to the bottoms of the boxes.

It has been an object of the present invention to develop an auxiliary frame which may be readily applied to each end of an Andrews frame for the purpose of adapting it for the reception of a roller bearing journal box having provisions, including side lugs, for mounting it flexibly in the frame. The auxiliary frame contemplated by the present invention is such that a pair of downwardly extending guide columns or pedestals is provided, these being formed with channelled guideways adapted to permit angling of the roller bearing journal box relative to the frame. Attachment of the box to the frame may be effected solely by the employment of pins adapted to be inserted through openings in the pedestals. These pins, furthermore, are necessitated simply for the purpose of retaining the box in the frame when the truck is lifted from the tracks. In the normal use of the structure no separate means of holding the box in proper relation to the frame is required to function and the pins mentioned will not interfere with the desired freedom of action.

A particular feature of the auxiliary frame is the provision of strengthening means at the corners where the downwardly extending columns or pedestals are joined to the horizontal, connecting member of the frame. This reinforcement at the corners enables the use of simple attaching means for the journal box, as mentioned, and permits the elimination of a tie bar or similar reinforcing

means connected across the lower ends of the pedestals beneath the box. The auxiliary frame is preferably rigidly attached to the main frame as by means of rivets passing through the bolt holes already provided in the Andrews type of frame. 55

Other objects and advantages of the invention will appear from the detailed description of an illustrative form of the same which will now be given in conjunction with the accompanying drawings in which: 60

Fig. 1 is a side view, partly in elevation and partly in section, of one end of an Andrews type of frame having the features of the invention applied thereto. 65

Fig. 2 is a plan view of the construction shown in Fig. 1 with portions of the frame cut away to more clearly disclose certain features. 70

Fig. 3 is a detail view partly in elevation and partly in section of the auxiliary frame of the present invention, and 75

Fig. 4 is a vertical sectional view taken substantially through the center of the journal box and side frame. 80

Referring now to the drawings, there is illustrated a portion at one end of a side frame 10 of the Andrews type having the tension and compression members, including the top arch bar 11 and bottom arch bar 12, cast integral. This frame may in general be similar to that illustrated in the patent to Lamont, No. 1,009,979, granted November 28, 1911. A flat under-surface 13 is provided on the frame, this surface being normally adapted to cooperate with the flat upper surface of an arch bar type of plain bearing journal box. Suitable bolt holes 14 are provided through bosses on the lower flange of the frame for the reception of the attaching bolts normally employed in securing an arch bar box to the frame. 85

According to the present invention an auxiliary frame 15 is provided having a pair of downwardly extending columns or pedestal portions 16 and 17 and a horizontal, connecting portion 18. The latter is formed with a flat, upper surface 19 adapted to cooperate with the surface 13 of the main frame. Openings 20 are formed through the portion 18 in 100

alinement with the openings 14 in the main frame and rivets 21 or similar means may be passed through the alined openings to rigidly secure the main and auxiliary frames together. In order to strengthen the downwardly extending guides or pedestals, and particularly at the corners at which they join the portion 18, these guides are provided with outwardly extending flanges 22 and 23, each flaring outwardly from the lower ends of the guides toward the upper ends of the latter. The flanges 22 have an upwardly extending portion 24 which, as best shown in Fig. 1, cooperates snugly with the end of the main frame and provides a smoothly curved upper surface as an extension of the upper edge of the tension member 11. The upper edge 25 of the flange portions 23 is inclined in the direction of the compression member 12 and preferably at a slightly greater angle to the horizontal so as to provide a small clearance as shown. Inwardly projecting flanges 26 are provided at each side of each of the pedestals; these flanges give additional strength and rigidity to the auxiliary frame. To increase the reinforcement afforded by the inwardly extending flanges, the latter are enlarged at their upper ends 27 where they are joined to the horizontal portion 18. This enlargement is substantially to the maximum extent permitted by the contour of the roller bearing journal box which is to be received between the pedestals, as will more clearly appear hereinafter.

Within the auxiliary frame there is adapted to be mounted a roller bearing journal box 28 having side lugs 29 adapted to fit into the channels provided between the side flanges of the pedestals 16 and 17. The relation between the side lugs and the pedestals is preferably the same as in my pending application Ser. No. 259,023, filed March 5, 1928. The faces 30 of the pedestals are preferably straight in a vertical direction and arcuate or curved in a direction transvers of the frame, as best shown in Fig. 2. Correspondingly curved surfaces 31 are provided on the ends of the side lugs, these surfaces having a slight normal clearance from the surfaces 30 so as to permit lateral angling of the box within the frame, and preferably also a slight bodily movement of the box between the pedestals. Sufficient clearance is provided between the sides of the lugs 29 and the inner surfaces of the flanges 26 to permit the desired angling.

At its top the box may suitably be provided with a recess surrounded by a rib 32 and adapted to snugly receive a bearing block or plate 33 of good wear resisting material. The upper surface 34 of this plate is preferably straight in a direction transverse to the axis of the journal but is arcuate or curved in a direction longitudinal of the journal to readily permit vertical angling. This upper

surface 34 of the plate is adapted to support the under surface 35 of the portion 18 of the auxiliary frame, which is preferably flat. On either side of the portion 18 of the auxiliary frame upwardly extending projections 36 may be provided on the box, these being adapted to cooperate with the side surfaces 37 of the portion 18. The surfaces 36 and 37 are preferably curved transversely of the box, the curvature of the surface 36 being greater, i.e. of shorter radius than the surface 37 so as to provide for easy lateral angling between the box and frame. A normal clearance of suitable extent is also provided between one or the other of the sets of cooperating surfaces 36 and 37 to allow for vertical angling of the box. These surfaces, furthermore, may advantageously be angled slightly to the vertical, as shown, to more effectively resist the angling and thrust forces

In order to retain the journal box between the pedestals when the car truck is lifted from the track, a pair of pins 38 may be provided and these may be passed through suitable openings 39 formed in the pedestals at a point slightly below the normal position of the lower edge of the side lugs 29 of the box. A cotter pin at one end and an enlarged head at the opposite end may serve to retain each pin 38 in position in the pedestals. As shown in Fig. 1, sufficient clearance is provided between the side lugs and the pins 38 to permit the desired angling movements of the box. Adequate clearance to permit angling and provide for easy assembly is also allowed between the flanges 26, including the enlarged portions 27 thereof, and the outer contour of the box.

Within the journal box any suitable roller bearing construction may be provided. For example a plurality of rollers 40, carried by suitable cages 41, may cooperate directly with an integral, hardened raceway provided on the inner surface of the journal box and these rollers also bear upon a hardened race formed by the outer surface of a sleeve carried by the journal 42. Any appropriate means may be provided for properly lubricating the bearings and for accepting the end thrusts between the box and journal.

While one illustrative form of the invention has been disclosed in considerable detail, it is to be understood that various changes in the construction and arrangement of the parts may be made without departing from the general spirit and scope of the invention as defined by the appended claims.

What I claim is:

1. A side frame structure comprising an Andrews type frame and an auxiliary frame rigidly secured thereto, said auxiliary frame having downwardly extending pedestals and a horizontal connecting portion, each of said pedestals having both inwardly and outward-

ly extending side flanges adapted to strengthen the corners between said pedestals and connecting portion.

2. In a structure of the class described a main side frame having integral tension and compression arch bar members terminating in an outward extension, and an auxiliary frame rigidly secured to said main frame, said auxiliary frame having downwardly extending pedestals with end walls and side flanges adapted to receive side lugs on a journal box, said end walls being curved transversely of said frame to cooperate with the ends of said side lugs.

3. In a structure of the class described a main side frame having integral tension and compression arch bar members terminating in an outward extension, and an auxiliary frame rigidly secured to said main frame, said auxiliary frame having downwardly extending pedestals with inwardly and outwardly extending flanges adapted to strengthen the corners of said auxiliary frame adjacent the upper ends of said pedestals, said inwardly extending flanges being adapted to receive between them the side lugs on a journal box.

4. In a structure of the class described a main side frame having integral tension and compression arch bar members terminating in an outward extension, and an auxiliary frame rigidly secured to said main frame, said auxiliary frame having downwardly extending pedestals with channels adapted to receive the side lugs of a journal box, said pedestals having openings therethrough adapted to receive pins for cooperation with the under surfaces on said side lugs.

5. In a structure of the class described a main side frame having integral tension and compression arch bar members terminating in an outward extension, and an auxiliary frame rigidly secured to said main frame, said auxiliary frame having downwardly extending pedestals with end walls and side flanges adapted to receive side lugs on a journal box, said end walls being curved transversely of said frame to cooperate with the ends of said side lugs and said side flanges having openings therethrough to receive pins for cooperation with the under surfaces of said side lugs.

6. In a structure of the class described a main side frame having integral tension and compression arch bar members terminating in an outward extension, and an auxiliary frame rigidly secured to said main frame, said auxiliary frame having downwardly extending pedestals with channels adapted to receive the side lugs of a journal box, said pedestals having openings therethrough adapted to receive pins for cooperation with the under surfaces on said side lugs, the lower ends of said pedestals being free and terminating above the bottom of said box.

7. In a structure of the class described a

main side frame having integral tension and compression arch bar members terminating in an outward extension, and an auxiliary frame rigidly secured to said main frame, said auxiliary frame having downwardly extending pedestals and a horizontal connecting portion, said pedestals including curved walls adapted to cooperate with the ends of side lugs on a journal box and outwardly extending flanges flaring outwardly from the bottom of the pedestals toward said connecting portion of the auxiliary frame.

8. In a structure of the class described a main side frame having integral tension and compression arch bar members terminating in an outward extension, and an auxiliary frame rigidly secured to said main frame, said auxiliary frame having downwardly extending pedestals and a horizontal connecting portion, said pedestals including curved walls for cooperation with the vertical ends of side lugs on a journal box and flanges flaring inwardly and outwardly from the lower ends of the curved walls to a point adjacent the upper ends thereof, whereby the joints between said pedestals and horizontal portion are strengthened.

9. In a structure of the class described a main side frame having integral tension and compression arch bar members terminating in an outward extension, and an auxiliary frame rigidly secured to said main frame, said auxiliary frame having downwardly extending pedestals and a horizontal connecting portion, said pedestals including curved walls adapted to cooperate with the ends of side lugs on a journal box and outwardly extending flanges flaring outwardly from the bottom of the pedestals toward said connecting portion of the auxiliary frame, the lower ends of said pedestals being free and being provided with openings adapted to receive pins for cooperation with the journal box side lugs.

10. In a structure of the class described, a main side frame having integral tension and compression arch bar members, and an auxiliary frame rigidly secured to the outer, joined ends of said members, said auxiliary frame including a pair of downwardly extending pedestals free at their lower ends and a horizontal connecting portion lying flat against a surface on said main frame, said pedestals being adapted to receive the side lugs of a roller bearing journal box for flexible connection therewith and being also adapted to receive retaining means for cooperation with said side lugs.

In testimony whereof, I have signed my name to this specification this 30th day of January, 1931.

ALBERT O. BUCKIUS.
